HANGER CLAMP

Donald E. Boden, Sale, and James B. Robertson, Timperley, Altrincham, England, assignors to Insul-8 Corp., San Carlos, Calif., a corporation of California

Filed Nov. 4, 1963, Ser. No. 77,273

Term of patent 14 years

(Cl. D54—13)

FIG. 1 is a perspective view of a hanger clamp showing our new design;

FIG. 2 is an end view thereof;

FIG. 3 is a side view thereof;

FIG. 4 is a plan view thereof; and,

FIG. 5 is a bottom view thereof.

The broken lines in FIGS. 2 and 3 are for illustrative purposes only.

We claim:

The ornamental design for a hanger clamp, as shown and described.
